DRILL STEEL GUIDE

Edward A. Rice, Claremont, N. H., assignor to
 Sullivan Machinery Company, a corporation of
 Massachusetts

Application September 16, 1944, Serial No. 554,516

8 Claims. (Cl. 255—51)

This invention relates to drill steel guides and more particularly to an improved guide for a drill steel of a mounted rock drill.

An object of the present invention is to provide an improved drill steel guide. Another object is to provide an improved guide for a drill steel of a mounted rock drill for guiding the drill bit during starting or "spotting" of a hole. A further object is to provide an improved drill steel guide embodying a pair of cooperating guide arms and having improved means for rigidly locking the arms together in steel guiding position. A still further object is to provide an improved drill steel guide which is of a comparatively rigid construction and relatively simple in design. Other objects and advantages of the invention will, however, hereinafter more fully appear.

In the accompanying drawing there is shown for purposes of illustration one form which the invention may assume in practice.

In this drawing:

Fig. 1 is a fragmentary side elevational view of the mounted rock drill equipped with an illustrative form of the improved drill steel guide.

Fig. 2 is a front end elevational view of the rock drill shown in Fig. 1, showing the drill steel in cross section.

Fig. 3 is a cross sectional view taken substantially on line 3—3 of Fig. 1.

Fig. 4 is a horizontal sectional view taken substantially on line 4—4 of Fig. 1.

Fig. 5 is a plan view of the guide.

Fig. 6 is a view similar to Fig. 2, showing the guide arms in released, non-guiding position.

Fig. 7 is a perspective view of the arm lock.

In this illustrative embodiment of the invention the improved drill steel guide is generally designated 1, and is shown associated with a rock drill 2 of the mounted drifter type. It will be evident, however, that the guide may be associated with other types of rock drills.

The rock drill 2 is of a conventional design and includes a usual guide shell 3 having longitudinal guideways 4 in which are slidably received longitudinal guides 5 on the cylinder 6 of a hammer motor 7. Attached to the front end of the motor cylinder is a chuck housing 8 containing a usual chuck for receiving and supporting the shank of a conventional drill steel 9 carrying a drill bit 10. The motor cylinder contains a usual reciprocable hammer piston which percussively actuates the drill steel during the drilling operation. Since the rock drill is of a well known construction, further illustration and description thereof are herein unnecessary.

Now referring to the improved drill steel guide 1, it will be noted that attached as by parallel bolts 11, 11 to the front end of the guide shell 3 is a pair of front and rear transverse plates 12 and 13 maintained in longitudinally spaced relation by spacing sleeves 14 interposed between the plates on the bolts. Pivotedly mounted on the spacing sleeves between the transverse plates are the hubs 15 of a pair of cooperating guide arms 16, 16. Thus the arms are pivoted on axes parallel to the longitudinal axis of the drill steel, and swing in transverse planes. The arms have appropriately shaped guiding portions 17, 17 adapted to embrace the body of the drill steel when the arms are moved together. Each arm has a lateral projection 18 at its inner side and when the arms are together, the projection on each arm overlies the guiding portion of the other arm in the manner shown in Figs. 3 and 5. Each 20 of the guiding portions 17 has an opening 19, and the projections 18 have openings 20 which are in registry with the openings 19, when the arms are together. A lock 21 is provided for locking the arms together and this lock is preferably 25 formed of wire suitably bent into shape. This lock is generally of U-shape and has a loop portion 22 and leg portions 23, the latter being insertible in the registering openings in the arms for rigidly locking the arms together. By arranging the openings 19, 20 in the manner shown each leg portion 23 of the lock engages both arms. The free ends of the leg portions are outwardly bent as at 24 and are preferably beveled at their outer sides at 25. The bevels facilitate insertion of the leg portions into the arm openings and the outwardly bent ends 24, when the lock is in locking position, prevent easy release of the legs from the openings. Accordingly, the lock serves as a spring clip and must be 30 forced into and out of locking position.

The general mode of use of the improved drill steel guide will be clearly apparent from the description given. When the guide arms are swung about their pivots into the position shown in Figs. 45 2 and 3 and the lock 21 is placed in locking position, the arms serve to guide the drill steel, thereby to center the drill bit during starting or "spotting" of a hole. The lock may be readily manually released simply by grasping the loop or 50 cross portion of the U and withdrawing the leg portions from the arm openings, and the arms may then be swung downwardly into their released non-guiding position shown in Fig. 6. When the guide arms are in this released position, they are located out of the path of move-

ment of the cylinder guides 5 so that the hammer motor may be fed forwardly along the guide shell past the guide.

As a result of this invention, it will be noted that an improved drill steel guide is provided which is comparatively rigid in construction, thereby firmly maintaining the drill steel in centered position during starting or "spotting" of a drill hole. By the provision of the improved projections overlapping the guiding portions of the guide arms and the registering openings in these projections and the guiding portions of the arms, the latter may be rigidly locked together in guiding position. The U-shaped lock serves firmly to lock the arms together and may be readily released when desired. Other uses and advantages of the invention will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a drill steel guide, a support, a pair of cooperating guide arms pivotally mounted on said support to swing relative thereto in transverse planes about axes parallel to the longitudinal axis of the drill steel, said arms provided with projections, the projection on each arm overlapping a portion of the other arm when the arms are together, and the arms and said projections having registering openings, and a lock having portions receivable in said openings for locking said arms together.

2. In a drill steel guide, a support, a pair of cooperating guide arms pivotally mounted on said support to swing relative thereto in transverse planes about axes parallel to the longitudinal axis of the drill steel, each arm having openings which register with openings in the other arm when the arms are together, and a lock having portions receivable in said openings for locking said arms together.

3. In a drill steel guide, a support, a pair of cooperating guide arms pivotally mounted on said support to swing in transverse planes about axes parallel to the longitudinal axis of the drill steel, said arms having guiding portions which embrace the body of a drill steel when the arms are together, and a lock having spaced portions each engageable concurrently with both of said guiding portions for locking said arms together in guiding position.

4. In a drill steel guide, a support, a pair of cooperating guide arms pivotally mounted on said support to swing in transverse planes about axes parallel to the longitudinal axis of the drill steel, said arms having guiding portions and projections, the projection on each arm overlapping the guiding portion of the other arm when said arms are together, said projections and said guiding portions having registering openings, and a lock having portions receivable in said openings for locking said arms together.

5. In a drill steel guide, a support, a pair of cooperating guide arms pivotally mounted on said support to swing relative thereto in transverse planes about axes parallel to the longitudinal axis of the drill steel, said arms provided with portions which overlap when the arms are together, said overlapping portions having registering openings, and a lock having portions receivable in said openings for locking said arms together.

6. In a drill steel guide, a support, a pair of cooperating guide arms pivotally mounted on said support to swing in transverse planes about axes parallel to the longitudinal axis of the drill steel, said arms provided with portions which overlap when said arms are together, said portions having registering openings, and a U-shaped lock having leg portions concurrently receivable in said openings for locking said arms together in guiding position.

7. In a drill steel guide, a support, a pair of cooperating guide arms pivotally mounted on said support to swing in transverse planes about axes parallel to the longitudinal axis of the drill steel, said arms provided with portions which overlap when said arms are together, said overlapping portions having registering openings, and a U-shaped lock having leg portions receivable in said openings for locking said arms together, said leg portions being laterally bent at their free ends so that they spring laterally upon insertion in said openings, and said bent portions when they pass through said openings serving to hold said lock in position.

8. In a drill steel guide, a support, a pair of cooperating guide arms pivotally mounted on said support to swing in transverse planes about axes parallel to the longitudinal axis of the drill steel, said arms provided with portions which overlap when said arms are together, said overlapping portions having registering openings, and a U-shaped lock having leg portions receivable in said openings for locking said arms together, said leg portions being beveled to facilitate insertion thereof in said openings.

EDWARD A. RICE.
